UNITED STATES PATENT OFFICE.

DUNCAN D. McBEAN, OF NEW YORK, N. Y.

METHOD OF BUILDING FOUNDATIONS FOR SUBAQUEOUS TUNNELS.

1,272,479.

Specification of Letters Patent. Patented July 16, 1918.

Original application filed February 21, 1916, Serial No. 79,594. Divided and this application filed September 13, 1916. Serial No. 119,802.

To all whom it may concern:

Be it known that I, DUNCAN D. McBEAN, a citizen of the United States, residing at New York, in the county and State of New

5 York, have invented certain new and useful Improvements in Methods of Building Foundations for Subaqueous Tunnels, of which the following is a full, clear, and exact description.

10 This invention is an improvement in the methods of preparing the foundations for subaqueous tunnels, dock walls and piers and for deepening river and channel beds, and is designed with special reference to a 15 saving in the amount of labor and expense involved in such work. This application is filed as a division of an application No. 79,594, filed by me on February 21st, 1916, and patented March 26, 1918, No. 20 1,260,416.

I have heretofore devised and patented methods and means for constructing tunnels, more fully set forth in Letters Patent Nos. 745,454; 745,456; and 745,457, dated December 1, 1903; and Nos. 797,524 and 797,525, 25 dated August 15, 1905, in which, as a definite feature characteristic to all, provision was made for the building of a fixed working chamber on the site of each tunnel section.

30 In other words, the plan in general was first to dredge out as far as convenient or practicable, the space in which the work is to be done, to then construct around and inclosing the space in which the structure is to be 35 built, a working chamber, practically water and air tight, to then pump the water out of such chamber, replacing it with air under sufficient pressure to equalize the load of superincumbent water, and to carry on the 40 work of tunnel construction within this fixed working chamber. The several patents mentioned above cover this general method and certain detailed improvements upon the same.

45 In all of these methods and inventions the tunnel foundations were prepared by driving piles into the bottom or site and cutting them off with appliances working from above the surface of the water.

50 Numerous patents have been granted and plans proposed for building tunnels or sections of the same at the surface of the water and lowering them into a trench dredged out from the bed of a river or other body of

water, but none of them have disclosed a 55 practicable form of movable chamber or any device of that nature for unwatering the site in which is to be prepared a foundation for the support of the tunnel in advance of sections thereof lowered upon the bed of the 60 trench, and these are only some of the objections which are present in the usual methods of subaqueous tunnel construction. Other objections, however, exist in such cases, mainly in that there has always been re- 65 quired a fixed working chamber or caisson for each length of tunnel and that the tunnel proper must be built within a subaqueous working chamber, instead of being completed or nearly so, at the surface and then 70 lowered into place.

With a view to obviating these and other difficulties, and more especially as an improvement on the methods set forth in my several patents above enumerated, I have 75 devised a plan for carrying on such work that presents many and distinct advantages. According to my present invention, I proceed as follows:

I build what may be termed a submarine 80 locomotive working chamber or dredge, that is to say, an open bottom compressed air chamber forming the lower portion of a submarine vessel, which has water ballast tanks in its upper part, and which is provided with 85 suitable means and appliances for raising and lowering the vessel in the water. The device is preferably equipped with pipes extending from the air chamber through the vessel and overlying water to air locks above 90 the surface of the body of water.

This vessel is lowered onto the bottom of a body of water and utilized to excavate a trench or to sink into a previously dredged one and is adapted to travel horizontally on 95 the river bed or trench bottom, preferably on rails laid temporarily on the tunnel foundations as they are progressively built. The compressed air chamber is preferably equipped with machinery and appliances of 100 suitable character for preparing the tunnel foundations and moving the vessel forward or backward as these foundations are put under it.

The bottom of the structure constituting 105 the working chamber, is open and forms a chamber in which the proper air pressure may be maintained to exclude the water and

to permit workmen to carry on the necessary operations involved in preparing subaqueous foundations or deepening river and channel beds. Through the entire structure 5 from top to bottom or alongside of the same, there may be provided suitable guide-tubes or passageways through which piles or sheeting may be driven from the surface, and in the compressed air chamber, circular 10 or other saws may be placed and adjustably mounted on supports therein, to cut off these piles or sheeting at the exact levels desired, and this without reference to the exact location of the piles with reference to the structure above it, or whether said piles have 15 been driven through the tubes in the structure or outside of it. In the case of a rock bottom the latter may be excavated and graded and cement columns or supports may 20 be laid upon it of the proper height so that in either case the preparation of a foundation at any exact and predetermined grade and alignment for tunnels in sections of any length is greatly facilitated.

25 The working chamber may be equipped with a dredging plant the suction pipes passing through the vertical walls and bottom of the structure. These pipes may be pivoted when so desired, and means may be 30 employed for adjusting the position of the same when pivoted, controllable, preferably, within the compressed air chamber, which pipes communicate with suitable pumps within the air chamber, whereby mud, silt 35 or other soft material from the sides, bottom and ends of the trench in which the structure is working may be removed by the pipes and raised to scows on the surface. In this way any material which may cave 40 from the sides or ends of the trench, or any silt that may flow into it, may be removed, thereby insuring the structure from being buried or blocked in its motion horizontally on its tracks by material collecting in the 45 trench about it, and the structure may lower itself to a depth greater than its height by excavating under it, through freeing itself from skin friction on its sides and ends, by pumping out sufficient of the material exterior to it, and thus the structure is enabled 50 to run back on its temporary tracks and clean off any debris, mud or silt that may have collected on the finished foundation behind it, and the temporary tracks 55 may thus be removed in advance of a tunnel section being lowered thereon. The tracks upon which the structure may run may be laid on the bottom or on a previously prepared foundation, and may be extended to 60 any distance.

The structure is preferably arranged with devices between it and the tracks to permit raising it above the latter to a height sufficient for it to overtop boulders or other ob-

stacles in its path, or, in cases where the 65 foundation is to be built on an inclined grade, to permit the raising and holding of the vessel in position, so that the bottom of the working chamber will be level while it is traveling thereon, or while work on an 70 inclined grade is being done under it. For this reason it is preferable to provide means on the trucks on which the structure rests for raising or lowering one or both ends of the same. 75

Another purpose in raising and lowering the structure is in the fact that it will be advantageous to raise it a few inches to permit the cutting off of the piles or sheeting, especially those driven outside of the structure, in the water a few inches below its surface in the working chamber, and then after they are cut off to lower the structure again and to increase the air pressure within the working chamber sufficiently to lower 85 the surface of the water under it below the top of the cut off piles or sheeting. This enables the workmen to cap the piles, to test them for levels or to excavate the material inclosed by the sheeting, or to otherwise prepare the foundation about the piles and to brace them in case the foundation which they provide is above the water bed. 90

The structure may be run forward or backward over the rails as may be necessary 95 so that a foundation for a tunnel may be built in full view, in air, instead of being constructed under water, or by means of fixed working chambers.

These and other results which are secured 100 by my invention tend to very greatly reduce the cost of tunnel construction and very materially lessen the labor and difficulty experienced in such work. In addition to providing a cheap and ready means of laying 105 tunnel sections, lowered successively to their final position in the ordinary way, the invention affords a means for carrying out other and entirely new processes of constructing tunnels, as by building up their 110 sections while they are floating in an upright position in the water, and then tipping them onto a substantially horizontal foundation, an invention which is not further herein described, as it has been made the 115 subject of other applications.

Referring now to the drawings hereto annexed, which illustrate the manner above outlined of carrying out the invention:—

Figure 1 is a sectional view of what I 120 have referred to as my submarine locomotive chamber or dredge, a structure of the general character and dimensions of a section of a tunnel to be laid and generally of somewhat greater length than width. In this figure, 125 the section is along the line of the greater dimension.

Fig. 2 is a sectional view of the structure

lying over a foundation prepared in a rock trench.

Fig. 3 is a sectional view of the same structure equipped with dredging and other appliances and means for driving piles through the structure.

Fig. 4 is a similar view of the same parts, showing the means employed for advancing it along a previously excavated trench.

Fig. 5 is a somewhat enlarged view, illustrating more in detail the passageways through which piles are driven.

Fig. 6 is a sectional view showing the use of sheet piling in the preparation of a foundation for a sub-aqueous structure.

Fig. 7 is a sectional view illustrating the manner of carrying out the excavation of a trench and preparing a foundation in a manner permitted by the use of this invention.

Fig. 8 is a plan view showing a sheeting piling passage way at the top of the structure.

The general construction of the submarine excavating dredge is shown in Figs. 1 and 2. This consists of a box-like structure, provided at the top with closed compartments which serve as water ballast chambers, at the bottom with an open bottom chamber 2, and built in any proper and substantial manner with I-beams 4 at the top and bottom and beams 5 to support the partition 6 between the two or the upper and lower compartments. A tube 7, provided with the usual air locks for entrance into and egress from the compressed air chamber, may pass down through the structure vertically from the surface and opens into the lower compressed air compartment 2. This tube has a joint formed by flanges 47 secured together by bolts or other means which may be quickly and easily removed by a diver.

Extending down through the structure at proper points are a series of tubes 12 to serve as guides for piles, which may be introduced through them and driven into the material of the water bed from the surface. Similar guiding passages may be attached to the outside walls of the structure, if so desired, such as are commonly used for spuds in structures of this kind, as shown at 12^a in Figs. 2 and 6. When desired there may also be provided elongated openings 3 through which sheet piling may be driven so as to form a continuous air and water tight wall around the site of a submarine structure, so that when the ends of the sheeting project up into the compressed air within the working chamber, the material within the sheeting walls may be readily excavated to the depth requisite for the foundation of the structure to be placed thereon. The tubes 12, and 3, where they enter the compressed air compartment 2, have joints by means of which their lower ends may be removed after the

piles are cut off, and valves 15 are provided above such joints which may be closed when the lower ends of the tubes are detached.

As a further illustration of the appliances used with the structure, reference is made to Figs. 3 and 4. Upon the lower cross beams 70 4 suitable platforms are provided upon which is mounted a compressor 16, which receives the requisite free air from the surface through pipe 17, and a pump or pumps 18 connected to a pipe 19 running up to the 75 surface or other convenient point, where it is suitably bent over to discharge into a scow 20. From the pump 18 leads a horizontal pipe 21, extending out in branches 80 through the vertical side walls and below the bottom inside of the structure and connecting with suction pipes 24, pivotally connected thereto outside the vertical walls. It will be understood that there may be as many pumps 18 as are necessary and any suitable 85 number or arrangements of valve controlled suction pipes to work on any or all sides of or beneath the bottom of the structure.

The position of the pivoted suction pipes 24, which are not accessible from within the 90 chamber, may be controlled by any suitable means. For this purpose I have shown these pipes supported by ropes 25 running over pulleys 26 and carried through comparatively tight openings in the walls of chamber 95 2, within which they are wound upon a reel 27. Any suitable means other than this may be employed to adjust the position of pipes 24 from within the chamber, or otherwise.

In the compressed air chamber 2 is also 100 a motor 32 which is removably supported on the beams 4, and which drives by suitable beveled gearing a vertical shaft carrying a circular saw 33. Any suitable device may be employed to perform the functions of 105 this saw, the purpose of which is to cut off at any requisite level to which it may be adjusted, the piles or sheeting 13. It is intended that the saw shall be moved to the ends or sides of the structure and adjusted 110 to cut off below the lower cutting edge of the working chamber piles or sheet piling that may be driven outside of the structure.

When the structure is used for preparing foundations or for submarine dredging by 115 the operation of the devices above described, it is desirable that it should be movable along a predetermined level, and for this purpose I lay caps along the tops of the sawed off piles and run trucks upon rails 34 120 laid thereon. The cross beams 4 rest upon these trucks, and the whole structure is thus supported upon the trucks. Any means, such as blocks or tackle 37, controlled either from within or without the chamber 2, may 125 be employed to advance the structure as occasion may require, or it may be drawn back by a tackle 38.

The structure may be raised or lowered with respect to these trucks by jacks 39 placed between the trucks and beams 36 secured to the upper side of beams 4, thus providing for an elevation or depression of the structure for carrying out its intended functions, or for passing over obstacles encountered by it, and enables the bottom of the compressed air chamber to be kept on a level 10 when the structure is traveling on an ascending or descending grade.

When the bottom is rock and the depth to be excavated is too great for it to be done in one cutting, the length of the locomotive structure is made somewhat greater than the width of the trench necessary for the tunnel structure. The structure is then placed lengthwise across the site of the trench, and the first cutting is made of a 15 somewhat greater width than that required for the tunnel structure. After the first cutting is excavated the structure is then turned at right angles and lowered into the first cutting when the trench is deepened to the 20 depth required for the foundation of the tunnel. The proceeding followed in preparing the foundation is that bases or columns of concrete 40 are laid upon the rock bottom and are given the required height to 25 form a proper foundation, as shown in Fig. 2.

In Figs. 6 to 8 I have illustrated a plan of preparing foundations in trenches in the bed of a body of water which may be carried out by means of this invention. According to this plan a trench may be excavated in the river bed by an ordinary dredging machine or any other means, and carried down to within a few feet of the depth intended for the foundation. In this trench the submarine vessel may rest upon temporary tracks laid on planks or cross beams and brought up to the point where the dredged trench of less than the required 40 depth begins. The vessel is then raised by the jacks upon its trucks until its forward bottom edge is above the level of the excavated trench, and it is then forced forward for a certain distance over the latter.

50 The excavation down to the level desired for the foundation is then completed by the appliances carried by the submarine vessel. In the meantime, as the vessel is advanced, piles are or may be driven down through it, 55 and either during its progress or on its return movement, in case the piles have been driven at its rear, these piles are cut off at the proper level and utilized as a foundation, or, if need be, for the rails on which the trucks travel. In all cases the material underlying the structure is substantially unwatered by the air pressure in the chamber.

Any means known in the art may be utilized for lowering sections of a tunnel onto

the foundation prepared for them in a 65 trench as above described.

By means of this invention, I may lay 70 tunnels of any cross section or shape and I may also prepare the foundations for piers, dock walls and the like.

What I claim as my invention is:

1. The method of preparing foundations 75 for subaqueous structures herein described, which consists in lowering to the bottom of a river or other body of water a submarine locomotive structure having at its lower portion an open bottom compressed air chamber, unwatering the part of the site under the structure, dredging progressively a length of trench under the same, preparing 80 therein a foundation at the proper level, removing the structure from the prepared foundation and lowering thereon the structure intended for such foundation.

2. The method of building foundations 85 for subaqueous tunnels and the like placed thereon, which has been herein described, which consists in lowering to the bottom of a river or other body of water a submarine locomotive structure having at its lower portion 90 an open bottom compressed air chamber, unwatering the site of the foundation under the structure, excavating by suitable appliances contained in said chamber, progressively a length of trench, driving piles 95 through passages extending from the top to the bottom of the structure to form a foundation in the trench, and then lowering thereon the tunnel or other structure intended therefor.

3. The method of preparing foundations 100 for subaqueous tunnels and the like placed thereon, which has been hereinbefore described, which consists in lowering to the bottom of the river or other body of water 105 a submarine locomotive structure having in its lower portion an open bottom compressed air chamber, unwatering the site of the tunnel under the structure, excavating by suitable appliances contained in said chamber, 110 progressively, a length of trench driving piles in the bottom of the trench through passages extending from the top to the bottom of the structure and cutting them off at the proper levels to form a length of foundation in the trench, and then lowering thereon the tunnel sections intended therefor.

4. The method of building foundations 115 for subaqueous tunnels placed thereon, 120 herein described, which consists in lowering to the bottom of a body of water a submarine locomotive structure having at its lower portion an open bottom compressed air chamber, unwatering the site of the 125 tunnel foundation under the structure, excavating by appliances contained in said chamber a tunnel trench under the struc-

ture, driving piles in the bottom of the trench, cutting them off at the desired levels, laying tracks thereon and advancing the structure by trucks running thereon to progressively unwater and prepare lengths of foundation in proper alignment for tunnel sections to be lowered and laid thereon.

5. The method of building foundations for laying thereon subaqueous tunnel sections herein described, which consists in lowering a submarine locomotive structure having its lower portion formed as an open bottom compressed air working chamber and having one dimension greater than the width of the proposed tunnel, placing said structure lengthwise across the line of the proposed trench, unwatering the water bed under the structure, excavating under the said structure by appliances contained in the working chamber the trench to the required depth, then turning the structure at right angles and lowering it into the cut thus made, and then preparing the foundation for the subaqueous tunnel under same.

25. 6. The method of building foundations for subaqueous tunnel sections placed thereon, which consists in lowering to the bottom of a body of water a submarine locomotive structure having in its lower portion an open bottom compressed air working chamber, dredging by pipes leading through its walls into the compressed air chamber the material from about the structure to form a trench, raising the said material from the chamber to the surface and preparing a foundation in the trench through the open bottom of the compressed air chamber and then lowering and laying a section of the tunnel thereon.

40. 7. The method of progressively preparing foundations for subaqueous tunnels, which consists in lowering to the bottom of a body of water a submarine locomotive structure having in its lower portion an open bottom compressed air chamber, excavating a trench under the structure, preparing a foundation in the trench and advancing the structure by trucks running on rails laid upon said foundation.

50. 8. The method of progressively preparing foundations for subaqueous tunnels herein described, which consists in lowering to the bottom of a body of water a submarine structure having at its lower portion an open bottom compressed air chamber, excavating under the structure a tunnel trench, preparing therein a foundation, laying rails upon said foundation, and moving the structure on the same by trucks and raising or lowering the structure with respect to the same.

9. The method of preparing foundations for a subaqueous tunnel in a trench in the bottom of a body of water, which consists

in lowering to the bottom a submarine structure having an open bottom compressed air working chamber under it, advancing the structure on tracks laid in the trench, preparing progressively by appliances contained in the working chamber, a foundation in the bottom of the trench and lowering and laying tunnel sections thereon.

10. The method of preparing foundations for subaqueous structures which consists in lowering to the bottom of a body of water a submarine structure having in its lower part an open bottom compressed air working chamber, unwatering the bed under the structure, driving progressively sheet piling through passages in the structure around the intended site, and excavating the material between the walls of the sheet piling to the required depth for the foundation for the structure intended therefor.

11. The method of preparing foundations for subaqueous structures, which consists in lowering into a trench dredged in a water bed, a submarine structure having in its lower part an open bottom compressed air working chamber, unwatering the bottom of the trench under the structure, driving sheet piling through passages in the structure into the material underlying the structure and around the site of the subaqueous structure, excavating material between the walls of the sheet piling to the depth required and building the foundation thereon.

12. The method of preparing foundations for subaqueous structures, which consists in lowering onto the bottom of an overlying body of water, a submarine locomotive vessel having an open bottom compressed air working chamber, unwatering the water bed under the vessel by the air pressure in the working chamber, driving through passages in the vessel sheet piling in the material under the same around the site of the subaqueous structure, cutting off the piling by appliances within the working chamber slightly below the surface of the water therein, then lowering the vessel to bring the tops of the sheeting above the water level within the chamber, excavating the material between the walls of the sheeting to the required depth for the foundation laying on the foundation prepared under the vessel the section of the tunnel then advancing the vessel progressively over adjacent lengths of the site of the subaqueous structure and cutting out the sheet piling and walls as the structure is built in their place.

13. The method of building foundations for subaqueous tunnels, which consists in lowering onto the site of the tunnel a submarine locomotive structure having an open bottom forming a compressed air working chamber, unwatering the tunnel site under

the structure, dredging in advance of the structure the material overlying the tunnel site, driving piles in the material of the site, cutting them off progressively as the structure advances, by appliances in the compressed air chamber, laying thereon temporary tracks for trucks for carrying the structure and preparing under the structure as it advances a foundation for successive

10 sections of the tunnel.

14. The method of preparing foundations for a subaqueous tunnel, which consists in lowering onto a track laid in a trench dredged in the water bed, a submarine locomotive structure having an open bottom forming a compressed air working chamber, unwatering the tunnel site under the structure and preparing progressively lengths of foundation to receive tunnel sections lowered

20 thereon.

15. The method of preparing foundations for a structure whose base is below the surface of the body of water, which consists in maintaining on supports placed on the water bed, a submarine locomotive structure having an open bottom and forming a compressed air working chamber, unwatering lengths at the required depth of the site under the structure and preparing progressively by appliances contained in the working chamber lengths of foundation for the structure to be lowered thereon.

16. The method of preparing foundations for receiving subaqueous tunnel sections, which consists in supporting on trucks traveling horizontally on a prepared foundation in the water bed, a submarine structure having in its lower portion an open bottom compressed air working chamber, unwatering the tunnel site under the structure, dredging out the material from under and about the structure through the working chamber to the desired width and depth and preparing under the working chamber and through its open bottom a foundation for the sections of tunnel to be laid thereon.

17. The method of preparing foundations for receiving sections of a subaqueous tunnel, which consists in supporting upon trucks running on tracks laid on the tunnel site a submarine structure having at its lower end an open bottom compressed air working chamber, unwatering the tunnel site under the structure, excavating the said site to the required width and depth, preparing a foundation under the working chamber, moving the structure ahead over the tunnel site and leaving in the rear the foundation for the sections of tunnel.

18. The method of preparing foundations for subaqueous tunnel sections, which consists in lowering on to the water bed a submarine locomotive structure having at its lower end an open bottom compressed air

chamber, unwatering the water bed under the structure, removing the water bed material under and around it sufficiently to enable it to sink freely to the required depth, by pipes leading into the compressed air chamber from outside of the structure and preparing progressively under the working chamber a foundation for the sections of tunnel.

19. The method of building foundations for a subaqueous tunnel, which consists in supporting in a trench prepared in a water bed, a submarine structure having at its lower end an open bottom compressed air chamber, removing the material from under and around the structure into the compressed air chamber and sending it to the surface through tubes provided therefor, unwatering the tunnel site under the structure and preparing a foundation thereon to receive the tunnel sections as the structure is advanced.

20. The method of preparing foundations for subaqueous tunnel sections on an inclined grade, which consists in advancing in a prepared trench on trucks running on rails, a submarine structure having at its lower end an open bottom compressed air working chamber, adjusting the structure with respect to the rails so that its bottom is level, unwatering the tunnel site under the structure and preparing thereon the foundation for receiving the tunnel sections.

21. The method of building foundations for subaqueous tunnels, which consists in supporting in a prepared trench in the water bed, a submarine locomotive structure, unwatering the trench under the structure, driving piles from the surface of the water through passages in the structure, sawing off the piles at the required level within the structure and preparing by means of such piles the foundation for sections of the tunnel.

22. The method of building foundations for subaqueous tunnel sections, which consists in dredging a trench in the bed of a body of water to a depth somewhat less than that required for the foundation, advancing in such trench by traveling supports a submarine locomotive structure having an open bottom compressed air chamber under it, unwatering and excavating the trench under the structure to the required depth and preparing a foundation thereon to receive tunnel sections as the structure advances.

23. The method of preparing foundations for subaqueous tunnel sections, which consists in supporting in a trench dredged in the bottom of a body of water, a submarine locomotive structure having an open bottom compressed air chamber under it, unwatering the tunnel site under the working chamber, preparing foundations thereon, laying

tracks upon such foundation for trucks to support and advance the structure and removing such tracks to leave the foundations in the rear of the structure in condition to receive the sections of tunnel.

24. The method of deepening beds of rivers and other bodies of water, which consists in lowering onto the bed a submarine locomotive structure having under it an open bottom compressed air working chamber, ad-

vancing the structure on supports on the material of the water bed, unwatering the bed under the structure and removing the material therefrom into the working chamber and removing the same from said chamber to the surface.

In testimony whereof I, hereunto affix my signature.

DUNCAN D. McBEAN.
